LUFFING DAVIT

Marinus C. Le Geu, Hamburg, Germany, assignor to Ane Pieter Schat, Utrecht, Netherlands

Application September 27, 1938, Serial No. 231,983
In Germany September 30, 1937

1 Claim. (Cl. 9—22)

This invention relates to a luffing davit of the type, in which the top end of the davit arm or boom is engaged by an element, such as a screw spindle, by means of which the davit arm is adapted to be positively urged inboard and outboard.

My present invention has for its main object an improved davit of the type referred to, in which the davit arm is substantially free from bending and torsional stresses. With this object in view, my novel davit comprises a boom, the top end of which is connected to a lateral brace adapted to be pivoted to the ship's deck.

The invention will be further described with reference to the accompanying drawings, in which like references indicate similar parts throughout.

Fig. 1 is a side view of a ship's davit in accordance with the invention, the full lines indicating the normal inboard position of the davit, and the dotted lines the outboard position, i. e. the position in which the boat suspended from the davit is fully swung out.

Fig. 2 is a corresponding front view.

Figs. 3—8 are views showing in detail the construction of the upper end of the davit arm, and the forces acting thereon.

Fig. 9 is a side elevational view of second embodiment of the invention.

Referring now particularly to Figures 1 and 2, 1 denotes the davit arm or boom pivoted as at 2 to a stanchion 3 which is secured to the ship's deck 4. One end of a life boat 5 is suspended, by means of a tackle comprising blocks 6 and a rope 7, from a strap 8 secured to the upper portion of boom 1, it being understood that by manipulating the rope the life boat can be raised or lowered as desired.

The davit arm can be swung from its inboard towards its outboard position and vice versa by means of a screw spindle 9, one end of which is pivoted to an eye 10 at the upper end of the boom 1, the other end being rotatably housed in a casing 11, which itself is pivotally connected as at 12 to the stanchion 3. The screw spindle is adapted to be operated by means of a crank handle 13.

A diagonal brace or tie rod 14 is pivoted at its upper end to an eye 15 of the boom 1, and at its lower end to a bracket 16 secured to the deck 4.

It will be seen that in any position of the davit, the boom is kept in balance by three forces, viz., the tensions in the rope 7, in the screw spindle 9 and in the brace 14. These three forces are denoted by L, W and N, respec-

tively in Figs. 3—7, which show the head of the boom with the parts 8, 10 and 15 for attaching the boat 5, the screw spindle 9 and the brace 14, respectively. They can be resolved, in the well-known manner, into components parallel with 5 and at right angles to the axis of the boom 1.

Fig. 4 shows the resolution of the stress L in rope 7 into its horizontal component H and its vertical component V. In Fig. 3, the component V is further resolved into the forces P and O. 10

As will appear from Figs. 3 and 5, the stress in the spindle 9 and the tension N in the brace 14 are resolved into the components X, Y, and M, J, respectively, it being understood that the forces P and H are substantially equal to the 15 forces X and M, respectively.

Fig. 6 shows the boom head in transverse section and the forces acting at right angles to the axis of said arm. The moment of torsion or torque acting upon the boom is: 20

$$T=H.a-P.b$$

Figs. 7 and 8 show the forces acting in a direction parallel to the axis of the davit arm. The bending moments in the plane of swinging 25 movement of the boom, and in a plane at right angles thereto are, respectively:

$$B_1=O.h-Y.g-J.m$$

and

$$B_2=O.e+Y.d-J.c$$

30

25

35

According to the invention, the various dimensions a, b, c, d, e, g, h and m are preferably so chosen as to render the moments T, B₁ and B₂ substantially nil, whereby the davit arm 1 is substantially free from bending and torsional stresses.

Fig. 9 shows a further embodiment of the invention. Instead of being pivoted to the davit arm, the brace 14 is rigidly secured to the head, and also, by braces 17, 18, to the portion intermediate the ends of said arm. 40

What I claim is:

A luffing davit comprising a boom pivotally connected to a ship's deck, means for suspending a life boat from the top end of said boom, an element engaging the top end of said boom and adapted when operated to positively urge said boom inward or outward, and a lateral brace connected to said boom, said element and said brace being arranged in offset relation with the boom in such a manner that the torsional and bending moments acting upon said boom under the influence of a boat suspended therefrom are substantially nil. 45
